DIVERSITY RADIO RECEIVING SYSTEM

Charles Percy Beanland, Chelmsford, England,
assignor to Radio Corporation of America, a
corporation of Delaware

Application December 7, 1944, Serial No. 567,014
In Great Britain October 25, 1943

Section 1, Public Law 690, August 8, 1946
Patent expires October 25, 1963

4 Claims. (Cl. 250—20)

1

This invention relates to radio receivers and provides an improved receiver which can be used with but little modification either as an individual receiver, or as a constituent receiver in a diversity receiving system.

When it is desired to use, as constituent receivers of a diversity system, receivers which may also be used as individual receivers each having its own automatic gain controlling system, and to that end to arrange that the constituent receivers shall work into a common load, it is necessary to arrange that the automatic gain controlling system of the combined system shall respond to rapid changes in the intensities of potential arising from the received signal. This means that the automatic gain controlling system of the combined system must have a suitably small time-constant. The time constant of the automatic gain controlling system of each constituent receiver is, of course, largely determined by the electrical dimensions of the capacitor, and resistor in the decoupling circuit. It will be apparent that if the automatic gain controlling systems of a number of constituent receivers are merely connected together, the capacitors of the several decoupling circuits will, as a consequence, be connected in parallel so that the time constant will be so increased that the diversity receiving system, as a whole, does not respond to rapid changes of signal received by the constituent receivers.

The invention aims at overcoming the difficulty set out above arising from the employment of receivers adapted to be used individually, and having their own automatic gain controlling system, as constituents of a diversity receiving system using the said automatic gain controlling systems to control the gain of the system as a whole.

As will be apparent, the time constant of the automatic gain controlling systems of receivers which is designed to give satisfactory performance when the receivers are operating individually, is modified for suitable and efficient performance when the receivers are used as constituents of a diversity receiving system.

According to the invention, a diversity radio receiving system comprises a plurality of constituent receivers each of which embodies an automatic gain controlling system which includes an automatic gain load resistor to which the output of an automatic gain rectifier may be applied and from which automatic gain potentials are derived for application to amplifying stages of the receiver, in combination with a unit

2

common to all the constituent receivers which includes an input load resistor, to which the outputs from the automatic gain rectifier of said receivers are transferred from said automatic gain load resistors and applied in common, a valve to which potentials from across said input load resistor are applied, and an output load resistor for said valve, from which potentials are applied to the automatic gain load resistors of all the constituent receivers in common.

The said valve may be a diode-triode valve and may have its anode and cathode connected between the positive and negative terminals of a source of power, a resistor being included in the cathode lead between the said cathode and the negative terminal of said source.

The said negative terminal may be at a potential which is lower than that of some suitable point on the said source of power which is at earth potential.

The said load resistors may have their one ends connected to a point at earth potential.

The automatic gain controlling system of this invention is so arranged that the individual receiver developing the highest automatic gain control voltage will control the gain of all the constituent receivers in the diversity receiver system in such a manner that those receivers having a smaller input signal are rendered less sensitive. In this way, the signal-to-noise ratio of the complete diversity receiver is maintained at a satisfactory level in spite of rapid and substantial changes in voltage derived from signal received by the several receivers.

An arrangement for carrying the invention into effect is illustrated in the accompanying drawing. In the drawing, three receivers R1, R2, and R3 are indicated, the former by an automatic gain diode 1, time constant circuit 2, two terminals 3 and 4, and load resistor 5. Receiver R2 has terminals 6 and 7, while receiver R3 has terminals 8 and 9. Receivers R2 and R3 are shown in block diagram since their circuits are similar in every respect to that of receiver R1. The anode 1a of automatic gain diode, such as 1, in receiver R1, is disconnected from its normal connection to load resistor 5 and connected instead to a conveniently accessible terminal 3, on the receiver, say at the back thereof. The end of the load resistor 5, to which the said anode is normally connected, is also connected to a conveniently accessible terminal, such as 4, adjacent to terminal 3. Connection 16 and 17 go to the grid circuits of radio frequency and inter-

mediate frequency amplifiers (not shown) of receiver R1. By the potentials appearing at these connections the gain of the amplifiers is controlled in a manner well known. The circuit arrangement in receivers R2 and R3 is exactly as shown and described with reference to receiver R1 and is therefore not separately described. When it is desired to operate such a receiver independently, that is not as a constituent receiver of a diversity receiving system, these two terminals 3 and 4 are connected together, and normal connections are thereby established. When, however, it is desired to use such a receiver as a constituent receiver of a diversity receiving system, the two terminals 3 and 4 are disconnected from each other and terminal 3 of the receiver under consideration is connected to a corresponding terminal 6 and 8 on other constituent receivers, as R2 and R3, and to one end of an input resistor 10 whose other end is connected to earth. It is to be observed that the terminals of the pair 6, 7, also the pair 8, 9 on these other receivers are also disconnected from each other. One end of resistor 10 is connected to the grid 22 of a double-diode-triode valve 11. Since this resistor now replaces the automatic gain resistors, similar to 5, of a plurality of receivers, its resistive value must be kept to the same order of magnitude, that is it must be high. The anode 12 of the triode portion of the double-diode-triode valve 11 is connected to the positive terminal indicated at +210V of a suitable source of high-tension energy. The cathode 21 is connected through a resistor 13 to a point on said source at a suitable negative potential indicated at -120V. The two anodes 14 of the diode portion of the double diode-triode valve are connected together and to one end of a potentiometer resistor 15. The resistive value of this potentiometer resistor is small so as to provide a small time constant, since it is an essential condition that the time constant of the combined automatic gain controlling circuit be kept as low as possible in order that the receivers may quickly respond to the fading of the signal as received by them. It is apparent that if the automatic gain controlling circuits were merely connected together, the sum of the decoupling capacities of the several systems would provide a time constant which would be bigger than would be tolerable. Terminals 4, 7, and 9 are the terminals to which the automatic gain load resistors in each receiver are individually connected. These terminals may, however, be connected in common to the slider on said potentiometer resistor 15 so that a controlled automatic gain potential may be fed back to the automatic gain resistors, similar to 5 of all the receivers in common.

The system operates as follows: A negative potential will appear across input resistor 10 due to signal picked up on any constituent receiver. This potential applied to the grid 22 of double-diode-triode valve 11 will decrease the current therethrough. The potential of the cathode 21 of the valve will consequently follow that of the grid, that is, it will go negative. The difference of potential between the anodes 14, 14 and cathode 21 of the diode portion will thus increase and the diode portions will consequently become conductive. The effective potentials of the anodes 14, 14 of the diodes and of the upper end of the potentiometer resistor 15 will become negative so that a negative potential will be fed back to the upper end of the automatic gain load resistors, such as 5, by way of the connection from the top on resistor 15 to terminals 4, 7, 9 of the

constituent receivers and thence, over leads 16 and 17 to the controlled intermediate and high frequency valves respectively of these receivers. The automatic gain potential for the intermediate frequency valves of the several constituent receivers is preferably taken from the top of the several automatic gain load resistors, as 5, whilst that for the high frequency valves is taken from a point lower down on these resistors.

10 If desired, switches as 18, 19, and 20 may be provided so that the automatic gain controlling arrangements of any of the receivers may be individualized.

I claim:

15 1. A radio receiving system comprising a plurality of constituent receivers each including signal detecting means and an automatic gain control circuit, each of said receivers having a terminal connected to said detecting means to receive the output thereof and a terminal connected to said automatic gain control circuit to feed an automatic gain control voltage thereto, a combining circuit having an input and an output, means for coupling all of said detecting means terminals to said combining circuit input and means for coupling all of said automatic gain control circuit terminals to said combining circuit output, said combining circuit including a thermionic discharge tube having a plurality of 20 cathodes to anode discharge paths therein and a control electrode for influencing the cathode to anode current in one of said paths, said combining circuit input being connected to said control electrode.

25 30 35

2. A radio receiving system comprising a plurality of constituent receivers each including signal detecting means and an automatic gain control circuit, each of said receivers having a terminal connected to said detecting means to receive the output thereof and a terminal connected to said automatic gain control circuit to feed an automatic gain control voltage thereto, a combining circuit having an input and an output, means for coupling all of said detecting means terminals to said combining circuit input and means for coupling all of said automatic gain control circuit terminals to said combining circuit output, said combining circuit including a thermionic discharge tube having a plurality of cathodes to anode discharge paths therein and a control electrode for influencing the cathode to anode current in one of said paths, said combining circuit input being connected to said control electrode, said discharge paths having a portion of their external circuits in common and said combining circuit output including a resistor connected from the anode of the other of said cathode anode paths to ground.

3. A radio receiving system comprising a plurality of constituent receivers each including signal detecting means and an automatic gain control circuit, each of said receivers having a terminal connected to said detecting means to receive the output thereof and a terminal connected to said automatic gain control circuit to feed an automatic gain control voltage thereto, a combining circuit having an input and an output, means for coupling all of said detecting means terminals to said combining circuit input and means for coupling all of said automatic gain control circuit terminals to said combining circuit output, said combining circuit including a thermionic discharge tube having a plurality of cathodes to anode discharge paths therein and a control electrode for influencing the cathode to

anode current in one of said paths, said combining circuit input being connected to said control electrode, said discharge paths having a portion of their external circuits in common and said combining circuit output including a resistor connected from the anode of the other of said cathode to anode paths to ground, said automatic gain control terminals being connected to an adjustable tap on said resistor.

4. A radio receiving system comprising a plurality of constituent receivers each including a signal detecting means and an automatic gain control circuit, each of said receivers having terminals, a terminal connected to said detecting means to receive the output thereof and a terminal connected to said automatic gain control circuit, a combining circuit having an input and an output, means for coupling all of said detecting means terminals to said combining circuit input and means for coupling all of said automatic gain control circuit terminals to said combining circuit output, said combining circuit including a thermionic discharge tube having a plurality of cathode to anode discharge paths

therein and a control electrode for influencing the cathode to anode current in one of said paths, said combining circuit input being connected to said control electrode, said discharge paths having a portion of their external circuits in common and said combining circuit output including a resistor connected from the anode of the other of said cathode to anode paths to ground, said automatic gain control terminals being connected to an adjustable tap on said resistor and means for selectively disconnecting a desired number of said constituent receivers from said combining circuit.
